INVENTOR

Henry W. Larsson

UNITED STATES PATENT OFFICE.

HENRY W. LARSSON, OF OAKLAND, CALIFORNIA.

PENCIL.

Application filed February 6, 1923. Serial No. 617,406.

My invention relates to a pencil, and to that type in which the leads are inserted and gradually projected by mechanical means, as the point wears.

5 One of the objects of the present invention is to generally improve and simplify pencils of the mechanical type, to make them easy to manipulate, and so arranged, that the leads employed for writing may easily be 10 renewed when desired.

Another object of the invention is to provide a pencil which consists of a point section and a barrel section, turnably mounted with relation to each other by a friction 15 joint, where a turning movement of either section, in relation to one another, transmits an advancing or retarding movement to the plunger that propels the leads.

Another object of the invention is to provide a release for the propelling mechanism, 20 when the pencil is parted for inserting a new lead, thus eliminating the necessity of returning the plunger, or propeller, by turning any part of the pencil.

25 Another object of the invention is to provide a magazine in the barrel of the pencil for holding spare leads, and means for partly elevating the leads out of the barrel, so that they may readily be picked out of the magazine as needed.

Another object of the invention is to provide the pencil with a mechanism that cannot be injured by over propelling or repelling of its plunger beyond its limits.

30 Further objects will hereafter appear.

The invention consists of parts and construction, combination and arrangements of parts, as hereafter more fully described and claimed, having reference to accompanying drawings, in which—

Fig. 1 is a central longitudinal section through the pencil.

Fig. 2 is a similar view, showing point, or lead receiver, parted from barrel section.

45 Fig. 3 is a section of barrel, with the magazine elevated, exposing spare leads.

Fig. 4 is a cross section on the line 4—4, Fig. 1.

50 Fig. 5 is a cross section on line 5—5, Fig. 2.

Referring to the drawing in detail, similar numerals refer to similar parts, throughout the several views.

The pencil consists of two cylindrical parts, the lead receiving, or point section, 55 and a barrel section 2. These sections are joined by a friction joint. The joint is formed by reducing the point section 1, and forming a bead 11, on its outer end. The side walls of this reduction are split at 60 10—10, to allow the bead 11, that is slightly larger in diameter, to enter the barrel 2, and expand into recess 19, formed in barrel 2, when the joint is assembled. This construction makes a turnable friction joint, with a 65 tendency to stay closed, but that may be parted, when a longitudinal force great enough is applied to force bead 11 out of recess 19.

The guide tube 3 is secured in the pointed end of point section 1. It acts as a guide 70 for the lead on its way to the tip 21, through which the lead 15 is forced. This tip 21 may be a snug fit, or split, to produce a friction on the lead. On the lower end of tube 3, a nut 18 is formed. This nut is split by a number of slits 22, and is sprung open, as shown in Fig. 2, and closed in Fig. 1. The function of this nut 18 is to close over, and engage the threaded plunger 5, when the two parts 75 of the pencil are joined, and to open and disengage plunger 5, when the pencil is parted.

In the barrel section 2, the tube 4 is mounted. Its upper end is bell shaped, and acts as a closer for the split nut 18, when the pencil parts are joined. In this tube 4 a threaded plunger 5 is mounted, free to slide therein; but prevented from turning therein, by key 8 formed on its lower end. This key 8 engages in a spline 7, cut in tube 4, as clearly 80 shown in Fig. 3. Plug 9, Fig. 1 forms a stop for plunger 5, and is secured in lower end of tube 4, as shown in Fig. 1. On the lower end of tube 4, a cup 6 is mounted and secured. This cup has a number of slits 14, forming its side walls into a series of springs, 85 that expand and friction against the inside walls of barrel section 2. One of the functions of cup 6 is to friction and follow barrel 2, when turned in relation to point section 90 100

1. This friction is great enough to do all useful work required to propel leads through the tip 21. But should any undue strain be set up in the mechanism, as propelling the plunger 5 beyond its limits, or should the lead be obstructed in its passage through the tip 21, and thus throw an overload on the mechanism, cup 6 will slip in barrel 2, by which it is actuated, thus taking care of the 10 overload, and preventing injury to mechanism.

Another function of cup 6 is to elevate the spare leads 16-17 out of magazine, as shown in Fig. 3. To do this work, the tube 4 to which cup 6 is fastened is manually raised in the barrel 2. The cup 6 frictions along the walls of barrel 2, until it reaches the recess 19. At this point, the spring walls of cup expand into the recess 19, and engage its 20 upper shoulder. This shoulder stops its upward movement, and thus elevated, the spare leads 16-17 shown in Fig. 3, can readily be picked out of magazine, as wanted.

The collar 12 is secured on tube 4, and 25 serves as a guide to center tube 4 in barrel 2, and to form a cover for the magazine when closed, as in Fig. 2.

In operation, the barrel section is turned relatively to the point section, to advance 30 the lead, or retard the plunger 5.

When the lead is all used up, and the plunger 5 has expelled the last part thereof, and it is desired to insert a new lead, the pencil is parted at its friction joint. In 35 doing so, the nut closer on tube 4 releases the spring nut 18. This nut springs open and disengages with the threaded rod 5. This rod is then free to follow the barrel section, and is manually returned to its bottom, or starting point. After parting pencil, the point section is held point downward, the magazine is elevated, as shown in Fig. 3, a spare lead is picked out of magazine, and dropped into point section. It drops 40 freely into the guide tube 3, until it reaches the tip 21, where it rests. The magazine is closed by manually depressing it into the barrel.

The pencil parts are now ready to be assembled, or joined. In assembling the two sections by the friction joint, the bead 11 positions the joint, when it engages in recess 19, the nut closer on tube 4 closes the spring nut 18, that engages the threaded 45 plunger 5. The pencil is now ready to operate, by turning one section in rotation to the other to advance the lead or retard the plunger.

I wish it understood that various changes, 50 in form, and proportion, may be resorted to, within the scope of the appended claims.

Having thus described my invention, what I claim and desire to secure by Letters Patent is—

1. A pencil comprising a pair of barrel

sections, turnably mounted in relation to each other, a lead passage and split nut carried in one section, a nut closer and a threaded rod carried in the other section, and means for imparting motion to said rod, 70 relatively to said nut.

2. A pencil comprising a pair of barrel sections, turnably mounted in relation to one another, by a turnable slip joint, a lead passage and split nut carried in one section, a nut closer and threaded rod frictionally carried in the other section, means for actuating threaded rod through split nut by a turning movement of either section. 75

3. A pencil composed of a point section 80 and a barrel section, a turnable slip joint connecting them, a lead passage and a split nut mounted in the point section, a slide nut closer with a slideable threaded rod carried in the barrel section, means for turning said threaded rod in split nut, causing a forward or backward movement of threaded rod, and means for disengaging split nut with threaded plunger.

4. A pencil composed of a point section 85 and a barrel section, a turnable slip joint connecting them, means for positioning said joint, a lead passage, a split nut carried in point section, a tube frictionally mounted in the barrel section, with a nut closer formed thereon, a threaded rod slidably mounted in said tube, means for closing nut over threaded rod, and means for opening said nut when the sections are parted.

5. A pencil composed of two sections, a point section carrying lead passage, a split nut and a rotating slip joint, a barrel section carrying a threaded rod slidably mounted in a splined tube, a nut closer formed on said tube, a friction cup carrying said tube in barrel, means for closing said split nut when joining sections, and means for opening split nut when pencil is parted. 100

6. A pencil composed of two sections, a pointed section carrying a lead passage, a split nut and a rotatable friction joint, a barrel section to receive said friction joint, means for positioning said joint, means for closing said split nut over threaded rod, means for rotating threaded rod in closed 110 split nut, and means for disengaging said split nut with threaded rod. 115

7. A pair of pencil sections joined by a positioning rotatable friction joint, a lead passage, a split nut carried in point section, a nut closer carried on a splined tube, said tube carrying a slideable threaded rod, a key on said rod engaging in said spline, a friction cup carrying said splined tube in the barrel section, forming a space for spare leads, means for retaining said spare leads in barrel section, and means for partly elevating said spare leads out of barrel section. 120 125

8. A pencil composed of two sections, a lead passage and an open split nut carried 130

in point section, means for closing said split nut over threaded rod carried in barrel section by joining said pencil sections, and means for actuating said threaded rod in closed threaded nut.

9. In combination, a pointed section and a barrel section, forming a pencil when joined, the point section carrying a lead pas-

sage and a split nut, a nut closer, a threaded rod, a friction cup, and a collar forming a 10 magazine for spare leads in barrel section, means for manually elevating said spare leads out of magazine substantially as set forth.

HENRY W. LARSSON.
